UNITED STATES PATENT OFFICE

EVERETT L. HOSKINS, OF PHILADELPHIA, PENNSYLVANIA, ASSIGNOR, BY MESNE ASSIGNMENTS, TO COOK LABORATORIES, INC., A CORPORATION OF DELAWARE

HYPODERMIC SYRINGE

Application filed January 4, 1923. Serial No. 610,565.

The object of my invention is to provide an improved hypodermic syringe of the class wherein the fluids to be injected may be normally sealed in containers or cartridges which can be inserted into the syringe instrument and the contents thereof ejected through the needle and without the necessity of introducing any of the fluid in an unconfined state within the barrel of the syringe.

In general, my improvements comprehend a syringe body having at one end an inwardly projecting short needle adapted to perforate a yielding closure or stopper in one end of a cartridge to be introduced and through which the fluid may be ejected by the forcible inward movement of a second closure at the other end of the cartridge, the syringe body being further provided with a detachable nipple carrying the hypodermic needle proper, whereby said hypodermic needle may be removed and sterilized and replaced without disturbing the inwardly projecting needle through which the contents of the cartridge pass in the use of the instrument.

My improvements further comprehend a hinged breech head at the rear of the syringe and adapted to be turned to one side when introducing or removing the cartridge and provided with means for locking the breech head in alignment with the body barrel of the syringe and forcing the cartridge down upon the needle and clamping it in position, said breech head further carrying a longitudinally reciprocable plunger adapted to be guided in axial alignment with the cartridge for forcibly driving inward the adjacent closure or stopper, causing it to act as a piston in ejecting the fluid through the two aligned needles.

The invention further comprehends the provision in the plunger of a hole or recess at its operating end adapted to receive the inwardly projecting tubular needle when no cartridge is present and thereby avoiding any damage to the point of said needle.

My invention also consists of other constructions, combinations and sub-combinations which, together with the features above

specified, are fully described hereinafter and more particularly defined in the claims.

Referring to the drawings: Fig. 1 is a side view of a hypodermic syringe embodying my improvements; Fig. 2 is a longitudinal sectional view of the same with portions broken away, whereby the illustration may be on a larger scale; Fig. 3 is a perspective view illustrating the general construction of the body, breech head and other connecting parts embodying my improvements; Fig. 4 is a side view of one of the cartridges, the ends thereof being in section to more clearly illustrate the closure features; and Fig. 5 is a cross section on line 5-5 of Fig. 1.

2 is the body of the syringe, being open at one end and closed at the other, the latter being provided with a head 3 having a screw threaded nipple 4 which is screwed into the closed end of the body, said head provided with a hole 5^a formed entirely through it and in which a short tubular needle 5 is secured and which extends through the nipple 4 so as to project a short distance into the interior of the syringe body. The head 3 is extended at its outer end and externally screw threaded to provide an extension upon which the nipple 6 is adapted to be screwed, whereby it may be readily detached when necessary. The nipple 6 is provided with an ordinary hypodermic needle 7, said needle and nipple being entirely separate from the needle 5 and adapted to be removed together when required to be subjected to a disinfectant fluid.

As the needle 7 is extended entirely through the nipple, (as is commonly understood), it is manifest that any fluid ejected from the interior of the syringe body through the short needle 5 will also be ejected through the nipple 6 and the hypodermic needle 7, it being further understood that the nipple 6 makes a liquid tight joint with the head 3, the screw connection between these parts being preferably slightly tapered.

At the other end of the syringe body there is provided a breech head 8 having a circular part 10 which fits over the end of the body 2, and is extended in a semi-circular portion whose ends are hinged at 9 to the

- opposite sides of the body. In this manner, the breech head may be turned at right angles to the body, as shown in Fig. 3, to expose the entrance into the body, or may 5 be turned upward in alignment with the body part 2 extending over the end thereof, as shown in Figs. 1 and 2. The part 10 of the breech head is bored out in alignment with the interior of the syringe body and is fitted 10 with a clamping part 13 having a screw threaded shank 14 by which it may be screwed relatively to the part 10 in a longitudinal direction to enter the syringe body and thereby lock the head in alignment with 15 the body during the use of the syringe, as more fully described hereafter. The screw threaded extension 14 of the locking part 13 may be provided with a milled wheel 15 by which to rotate it, when adjusting the part 20 13 into or out of locking position.
- The barrel 2 of the syringe is preferably open along its length at opposite sides, as at 2^a, and is adapted to receive a tubular glass cartridge 21 which is somewhat shorter 25 than the syringe body, to permit entrance of the locking and clamping part 13 and which clamps the cartridge in position upon the needle 5. The cartridge 21 loosely fits the interior bore 20 of the barrel of the 30 body, so that it may be readily introduced and removed when necessary. It is also desirable that the closed end of the barrel of the body be provided with a thin washer 26 of asbestos or other slightly yielding material 35 against which the glass of the cartridge may be received to insure a reasonably tight joint and prevent danger of cracking the glass tube in case of slight irregularities in its end edges.
- 40 This cartridge 21, containing the fluid 24, consists of a short glass tube sealed at one end by a perforable closure 23 which may be of rubber or other suitable material capable of being penetrated when the cartridge 45 is forced down upon the needle 5 by the locking and clamping part 13, as shown in Fig. 2. The cartridge is also sealed at the other end by a movable stopped or closure 22, also preferably of rubber, and said closure is desirably 50 positioned slightly below the end of the glass tube, so as to leave a slight recess 25 above it for a more ready entrance of the plunger end 17 when ejecting the fluid. The cartridge 55 is loosely placed within the barrel 2 of the syringe body and may be viewed through the window apertures 2^a, whereby the extent of the discharge of the fluid may be observed. The plunger for causing the ejection of the fluid consists of a long cylindrical 60 rod 16 having at its outer end a handle portion 19 and at its inner end a part 17 which loosely fits the interior of the cartridge tube 21, whereby it may press upon the movable stopper or closure 22 and freely travel 65 through the cartridge tube when ejecting the
- fluid therefrom. The plunger 16 is guided through a bearing formed in the locking and clamping part 13 and its screw threaded extension 14, as is clearly shown in Fig. 2, whereby when the breech head is turned into alignment with the syringe body and locked in said position by the locking and clamping part 13, a longitudinal movement of the plunger will cause it to enter the cartridge without danger of cracking the same. The end 17 of the plunger is preferably provided with a hole or recess 18 of a diameter amply sufficient to readily receive the needle 5 when the plunger is fully received in the syringe body, but it will be understood that, if desired, the hand part 19 may act as a limit stop in connection with the end of the extension 14 to limit the inward movement of the plunger so that it shall not quite reach the needle 5, and I, therefore, do not limit myself in this respect.
- The breech head 8 is also provided with a cross bar 12 which is journaled about the circular part 10 and held in position thereon by a nut 11, thereby permitting the said cross bar 12 to be movable about the longitudinal axis of the syringe when in use, said bar acting as a support for two of the fingers of the hand while the palm thereof is caused to act upon the handle part 19 of the plunger. In Fig. 3, I have shown the cartridge 21 slightly projecting from the barrel of the body 2 for the purpose of illustrating the general sleeved arrangement of these parts. When, however, they are in actual use, their relative positions are as indicated in Fig. 2, and the locking and clamping part 13 is advanced into the body 2 to lock the breech head in operative position.
- In employing my improved syringe, the breech head is swung back, as indicated in Fig. 3, a cartridge 21 (Fig. 4) is inserted into the metallic barrel of the body 2 with its closure 23 resting upon the point of the needle 5. The breech head 8 is then swung upward into the position shown in Figs. 1 and 2, and the locking and clamping part 13 is screwed inward within the barrel of the body 2 to lock the breech head in aligned position; and by a continued inward screwing, said part 13 presses upon the end of the cartridge and forces its other end down upon the needle 5, causing the same to penetrate the closure 23, as shown in Fig. 2, and with the said part 13 as indicated in dotted lines. Thereafter, the plunger 16 may be forced inward upon the outermost closure 22 of the cartridge, driving it forward as a piston and ejecting the fluid 24 through the needle 5 and thence through the nipple 6 and hypodermic needle 7. In this operation, it will be seen that the cartridge is hermetically sealed and by no possibility can the fluid contents thereof become contaminated; consequently, the purity of the medicament is preserved. When the injec-

tion has been completed and it is desired to remove the spent cartridge, the locking and clamping part 13 is screwed back and the plunger withdrawn into the positions of the solid lines shown in Fig. 2, and thereupon the

5 breech head is swung around, as shown in Fig. 3. Thereafter, the cartridge is grasped by the finger and thumb through the opposite openings or windows 2° in the body 2 and moved backward and from off the needle 5 and finally 10 out of the syringe. If only a portion of the fluid contents is used, the rubber closure 23 automatically seals itself and retains the contents for further use, if so desired.

15 The above described syringe may be used to advantage in making intraosseous and other injections requiring high pressures. In previous cartridge syringes, excessive pressure may at times force the pierced plug out of the 20 end of the cartridge, thereby causing loss of the medicament and soiling of the syringe and the person of the practitioner. This outward movement of the pierced plug is nearly always possible because a cartridge is not held 25 immovably by previously known syringes, but on the contrary, is capable of a slight longitudinal movement; and therefore when heavy pressure is exerted on the sliding plug, the pierced plug (through the intermediation of the incompressible medicament), is subjected 30 to an equal pressure, which may be sufficient to cause the entire cartridge to move back or away from the pierced plug, under the reaction stresses, finally exposing the inner end of 35 the plug, whereupon a violent discharge of the medicament takes place in all directions. The described syringe locks the cartridge immovably, thus making it impossible for the pierced plug to move beyond the end of the 40 cartridge body, thereby preventing accidental discharge of the medicament. This locking of the cartridge is also of advantage when piercing of the cartridge is accomplished after the cartridge is in place; there can then be 45 no displacement of the plugs by the inward thrust of the needle 5, consequently loss of the medicament and soiling of the syringe are prevented.

50 In the above description and in many of the appended claims the syringe is referred to as a hypodermic syringe. It will be readily understood that the syringe as disclosed herein may be used without change for various injections and for the application of fluid and 55 semi-fluid medicaments to tissues generally. Hence the word "hypodermic," wherever used, is to be considered as used descriptively and not restrictively.

It will now be apparent that I have devised 60 a novel and useful construction which embodies the features of advantage enumerated as desirable, and while I have in the present instance shown and described the preferred embodiment thereof which has been 65 found in practice to give satisfactory and

reliable results, it is to be understood that I do not restrict myself to the details, as the same are susceptible of modification in various particulars without departing from the spirit or scope of the invention.

Having now described my invention, what I claim as new and desire to secure by Letters Patent is:—

1. In a hypodermic syringe, the body portion provided at one end with an outwardly 75 extending ordinary hypodermic needle and an inwardly extending tubular needle, combined with a breech head hinged near the other end of the body and adapted to swing over the open end thereof, a longitudinally 80 adjustable locking part carried by the breech head and adapted to be adjusted into the open end of the syringe body to hold the head in alinement therewith, a reciprocable plunger having a sliding connection with said 85 breech head whereby it is guided axially through the syringe body and in alinement with the inwardly extending tubular needle thereof, a cartridge fitting the body and having a perforable closure at one end and a 90 longitudinally movable closure at the other end, said cartridge clamped in the body by means of the adjustable locking part and the pressure of the latter adapted to force the cartridge upon the inwardly projecting 95 needle to cause the same to penetrate through the perforable closure whereby communication may be had with the contents of the interior of the cartridge the plunger adapted to act upon the movable closure to cause it 100 to function as a piston for the cartridge, and wherein further, the locking and clamping part consists of a rotatable member adjustably screwed in the breech head and having a diameter approximately equal to the internal diameter of the open end of the body, 105 said rotatable member having a guide passage through it in which the reciprocable plunger is guided.

2. In a hypodermic syringe, the body portion provided at one end with an outwardly 110 extending ordinary hypodermic needle and an inwardly extending tubular needle, combined with a breech head hinged near the other end of the body and adapted to swing over the open end thereof, a longitudinally 115 adjustable locking part carried by the breech head and adapted to be adjusted into the open end of the syringe body to hold the head in alinement therewith, a reciprocable plunger having a sliding connection with said breech head whereby it is guided axially through the syringe body and in alinement with the inwardly extending tubular needle thereof, 120 wherein further there is provided a cartridge fitting the body and having a perforable closure at one end and a longitudinally movable closure at the other end, said cartridge clamped therein by means of the adjustable 125 locking part, the pressure of the latter 130

- adapted to force the cartridge upon the inwardly projecting needle to cause the same to penetrate through the perforable closure whereby communication may be had with the contents of the interior of the cartridge the plunger adapted to act upon the movable closure to cause it to function as a piston for the cartridge, and wherein further, the body part is provided on opposite sides with open window portions arranged longitudinally whereby the cartridge may be viewed through the body part and may also be grasped to withdraw it from off the inwardly extending needle upon completing the use of the instrument.
3. A hypodermic syringe comprising, in combination, means for holding a medicament dispensing cartridge; a hinged closure for said holding means; and a screw-actuated lock bridging the joint between said closure and holding means.
4. A hypodermic syringe comprising, in combination, a cartridge holder; a hinged closure therefor; a hollow screw engaging the closure with its threads and constructed and arranged to hold the closure and cartridge holder together; and a plunger slideable through said screw to dispense the contents of the cartridge.
5. A syringe of the class described comprising, in combination, a barrel constructed and arranged to receive a cartridge; means for piercing one end of the cartridge; a joint in the syringe permitting opening thereof for the insertion or removal of a cartridge; and a screw in the breech end of the instrument providing a lock for the syringe joint and also providing cartridge pushing means to force the cartridge against the piercing means.
6. A syringe of the class described comprising, in combination, a jointed cartridge carrier; a cartridge-piercing point; a screw locking the joint in the syringe; and means carried by the screw designed to engage the end of the cartridge to push it against the piercing point.
7. A syringe of the class described comprising, in combination, a barrel constructed to hold a cartridge; a hinged head at one end of the barrel designed to close the barrel; a canula for piercing the cartridge; a plunger for expelling the contents of the cartridge; and a cartridge pushing member, said member manually adjustable relative to the plunger for pushing the cartridge; both the plunger and cartridge pushing member being carried by said hinged head.
8. A syringe of the class described comprising, in combination, a body; a medicament cartridge held by the body and constructed and arranged to have its interior volume reduced for discharge of its contents; said body having a joint whereby it may be broken at the joint for insertion of the cartridge; and a locking member to secure the jointed parts of the syringe in operative position, said locking means engaging the end of the cartridge to clamp it immovably.
9. In a cartridge syringe, a cartridge holder having a cartridge-piercing canula at its fore end and having a breech head displaceable to permit endwise insertion of the cartridge; a hollow screw mounted in said breech head and adapted to be screwed therein against the butt end of the cartridge to thrust it forward and insure piercing by the needle; and a cartridge-operating plunger slideable in said screw and connected thereby to the head.
10. In a cartridge syringe, a cartridge holder having a hinged breech head; a hollow screw in said head cooperable with the body of the holder to lock the head in place, and adapted to be unscrewed to permit swinging the head laterally to allow endwise insertion of the cartridge; and a cartridge-operating plunger slideable in said screw and connected thereby to the head.
11. In a cartridge syringe, a jointed cartridge-holding and operating instrument having a cartridge-operating plunger and adapted to be opened for insertion of the cartridge and to be closed for operative use, said instrument comprising hinged or pivotally-connected parts adapted to be relatively displaced for opening the instrument and having an axially-adjustable locking screw, in which the plunger works, cooperable with the said parts to hold the instrument closed.
12. In a cartridge-syringe, a jointed cartridge-holding operating instrument having in its breech end a cartridge-operating plunger and constructed at its fore end to provide a cartridge abutment and to accommodate a cartridge-piercing needle, said instrument comprising parts permanently connected but relatively displaceable for opening the instrument to permit insertion of the cartridge and having an axially-arranged hollow screen, in which the plunger works, said screw adapted when the instrument is closed to be screwed against the butt end of the cartridge so as to thrust it forward, and said screw cooperable with said parts as a locking device to prevent their displacement and thus hold the instrument closed.
13. In a cartridge-syringe, a breech-loading cartridge-holding and operating instrument, jointed to permit swinging its rear portion relative to its front portion for opening the instrument to permit insertion or withdrawal of the cartridge; said front portion embodying an abutment for the fore end of the cartridge and adapted to accommodate a cartridge-piercing needle; and a cartridge-operating plunger and hollow screw in which said plunger works carried by said rear portion, said screw adapted to bridge the jointed parts of the instrument to lock the same in closed condition and to bear on the butt end

of the cartridge and thrust it forward against said abutment.

14. In a cartridge-syringe, a breech-loading cartridge-holding and operating instrument, jointed to permit swinging its rear portion relative to its front portion for opening the instrument to permit insertion or withdrawal of the cartridge; said front portion embodying an abutment for the fore end of the cartridge and adapted to accommodate a cartridge-piercing needle; and a cartridge-operating plunger and hollow screw in which said plunger works carried by said rear portion, said screw adapted to bridge the jointed parts of the instrument to lock the same in closed condition.

15. In a cartridge-syringe, a jointed cartridge-holding and operating instrument, adapted to be opened for introduction of a cartridge and to be closed for operative use, said instrument embodying a cartridge-operating plunger and an associated screw to lock the instrument closed.

16. In a cartridge-syringe, a jointed cartridge-holding and operating instrument adapted to be opened by disaligning its front and rear parts to permit introduction of a cartridge and to be closed for operative use by straightening the instrument, said instrument having its fore end constructed to receive a cartridge-piercing needle and having a plunger in its breech end and embodying an axially-arranged screw to lock the instrument closed.

35 17. In a cartridge-syringe, a breech-loading cartridge-holding and operating instrument embodying a plunger in its breech end, and embodying in its fore portion a head affording an abutment for the fore end of the cartridge and having an opening to accommodate a cartridge-piercing canula, said instrument jointed to permit lateral displacement of the plunger out of alignment with the normal axis of the instrument, with accompanying opening of the breech end, and embodying an axially arranged hollow screw, through which the plunger works, said screw adapted to lock the instrument in closed condition with the parts in alignment.

50 18. An instrument of the class described, for use with a cartridge having a pierceable stopper in its fore end, comprising a cartridge receiving barrel provided at its fore end with a head having a fine axial bore and a hypodermic needle detachably fixed on said head in communication with said bore, and a canula consisting of a hollow needle fixedly secured in said bore and protruding axially a substantial distance into said barrel to pierce through the said pierceable stopper; the instrument being constructed to permit endwise insertion of the cartridge through the breech end, and having means for operating said cartridge to expel its fluid contents

through the hypodermic needle via the said canula and communicating bore.

19. In an instrument of the class described for use with a cartridge having a pierceable stopper in its fore end, a cartridge-receiving barrel provided at its fore end with an axially-bored head and a canula consisting of a hollow needle fixedly secured in said bore and projecting axially a substantial distance into said barrel to pierce through said stopper, said canula being separate from but communicating through said bore with the delivery point of the instrument.

20. A cartridge syringe comprising, in combination, a cartridge embodying a sealed liquid-containing tube having a pierceable stopper in its fore end and having a piston plug; and an instrument comprising a cartridge holder having a canula to pierce said stopper and a plunger rod to force in said piston plug; the fore end of said instrument comprising an axially bored head, and said canula comprising a hollow needle fixedly secured in the bore of said head and extending axially into the instrument a substantial distance to pierce through said pierceable stopper, said canula being separate from but communicating through said bore with the delivery point of the instrument.

21. In a hypodermic syringe, the body portion provided at one end with an outwardly extending ordinary hypodermic needle and an inwardly extending tubular needle, combined with a breech head hinged near the end of the body most distant from the needle end thereof and adapted to swing over the end adjacent to which it is hinged; a longitudinally adjustable locking part carried by the breech head and adapted to be adjusted into the open end of the syringe body to hold said head in alignment with the body; and a reciprocable plunger having a sliding connection with said breech head and through the locking part, whereby it is guided axially through the syringe body and in alignment 100 with the inwardly extending tubular needle thereof.

In testimony of which invention, I hereunto set my hand.
